UNITED STATES PATENT OFFICE.

CHARLES H. NOWACK, OF OAK PARK, ILLINOIS, ASSIGNOR TO AMERICAN CAN COMPANY, OF NEW YORK, N. Y., A CORPORATION OF NEW JERSEY.

HERMETICALLY-SEALED BOX.

1,324,207.

Specification of Letters Patent.

Patented Dec. 9, 1919.

Application filed October 23, 1915. Serial No. 57,464.

To all whom it may concern:

Be it known that I, CHARLES H. NOWACK, a citizen of the United States, residing in Oak Park, in the county of Cook and State of Illinois, have invented a new and useful Improvement in Hermetically-Sealed Boxes, of which the following is a specification.

This invention relates in general to hermetically sealed boxes for the packaging of various products and has particular reference to boxes of sheet metal provided for this purpose.

A principal object of this invention is the provision of a metal or tin box sealed at the end or side through which access is to be had to the interior together with a cover which may be readily manipulated to cut the seal from the end of the box and thereafter serve as a closure for the box.

20 A particular object of the invention is to provide a cover having an efficient cutter provided without the addition of any extra members or parts and also without the addition of any material to provide the cutter.

25 Boxes of this character are sold to the packer in extremely large quantities and the construction of any cutting members and the fastening of such members after construction in place, while not costing appreciably 30 in the construction of each individual box, amounts to considerable in the aggregate.

Other objects and advantages of the invention will be apparent as it is better understood from the following description 35 when considered in connection with the accompanying drawing illustrating a preferred embodiment thereof.

On the drawings,

40 Figure 1 is a perspective view of a box embodying my invention;

Fig. 2 is a section taken vertically through the box and illustrating the method of forming the cutter;

45 Fig. 3 is a similar view showing the cover in cutting position;

Fig. 4 is a bottom partial view on a somewhat enlarged scale of the cover; and

Fig. 5 is a similar view showing the position of the cutter before being bent to final 50 arrangement.

For the purpose of illustrating my invention I have shown on the drawing a box consisting of a body A and a cover B. This body A is formed, in the present instance, 55 of a bottom 6 and a cylindrical side wall 7

which is engaged at its open end with the edge 8 of a sheet seal 9, the engagement, in the present instance, being formed by an interlocked seam 10 holding the seal 9 against an inwardly extending shoulder 11 which is 60 formed by depressing the cylindrical side wall 7 circumferentially at an appropriate height. The cover B is of sheet metal and the box body and the seal may be made also of metal or of any other appropriate material. The cover is provided with an integral downwardly extending cutter or cutting lip 12. This cutter is formed by making a V-shaped cut 13 in the body 14 of the cover and then bending the part set off downwardly to the position indicated on the drawing and so that it extends vertically when the box rests upon its bottom. The body 14 of the cover is preferably depressed to provide a raised circumferential part 15 adapted to fit over the seam 10, and the cover has, in the present instance, a downwardly extending circumferential flange 16 loosely fitting the outside of the box body.

When so constructed the box may be 80 packed and sealed by securing in place the seal 9 and merely placing the cover over the end thus closed. It may be opened by merely pressing down upon the cover to force the cutter 12 into the seal and then 85 rotating the cover about the body to cut out substantially the entire seal and give almost a full opening to permit removal of the contents.

The cover is preferably of heavier material than the seal or of material harder than the seal in order to facilitate the operation of the cutter. However, the V-shape of the cutter will cause it to operate effectively upon material having a wide range 95 of qualities by reason of the fact that the cutting surface presented to the seal, after the cutter has been inserted in the material, is inclined at an oblique angle to the plane of the material cut, thereby increasing the 100 resistive properties of the cover and increasing also the frangible quality of the seal.

It is thought that the invention and many of its attendant advantages will be understood from the foregoing description, and it will be apparent that various changes may be made in the form, construction and arrangement of the parts without departing from the spirit and scope of the invention 110

or sacrificing any of its material advantages, the form hereinbefore described being merely a preferred embodiment thereof.

I claim:

- 5 1. A box comprising a body the wall of which near the mouth of the box is bent inward and thence outward to form a solid inwardly extending horizontal shoulder, a severable seal supported on said shoulder, the margin of the body being interfolded with the margin of the seal and bent over inward to confine the seal on said shoulder, and a rotatable cover having a knife arranged near the inner edge of said shoulder.
- 15 2. A box comprising a body the wall of which near the mouth of the box is bent inward to form a seal-supporting shoulder, and a seal the margin of which is interfolded with the inwardly bent edge of the body to form a seam which secures the margin of the seal and confines the seal down against said shoulder, the seal being adapted to be cut by a knife operating near said shoulder.
- 25 3. A box comprising a body the side of

which near the mouth of the box is turned inward and thence outward to form an inwardly extending shoulder and thence upward, a frangible sheet seal supported on said shoulder and having its margin interseamed with the top margin of said body, and a cover fitting and rotatable on the box body and having a cutter blade located to operate on said seal near the inner margin of said inwardly extending shoulder. 30

4. A box comprising a body, a frangible sheet seal having its margin attached to the margin of the mouth of said body, a cover fitting and rotatable on the body and having a depending cutter blade, and a support 40 for the outer part of said seal carried by said body and extending inward close to the line of operation of said blade. 35

Signed in the presence of two subscribing witnesses.

CHARLES H. NOWACK.
